GEORGE D. BRECK, OF CLEVELAND, OHIO, AND WILLIAM J. MERTEN, OF PITTSBURGH, PENNSYLVANIA; SAID MERTEN ASSIGNOR TO SAID BRECK.

ARTICLE OF BODY-WEAR.

1,280,149.

Specification of Letters Patent.

Patented Oct. 1, 1918.

Application filed January 4, 1918. Serial No. 210,361.

To all whom it may concern:

Be it known that (1) GEORGE D. BRECK and (2) WILLIAM J. MERTEN, citizens of the United States, residing at (1) Cleveland, (2) Pittsburgh, in the county of (1) Cuyahoga, (2) Allegheny, and State of (1) Ohio, (2) Pennsylvania, have invented a certain new and useful Improvement in Articles of Body-Wear, of which the following is a full, clear, and exact description, reference being had to the accompanying drawings.

This invention relates to articles of body wear, such as boots, gloves, bandages, and other clothing members made primarily of rubber, artificial leather, and the like impervious substances, the same being so treated as to enable them to be worn or applied close to the body without danger or discomfort.

It is well known that leather, while substantially impervious to water, is sufficiently pervious to air to permit articles of clothing made therefrom to be worn close to the body, as in the case of boots, shoes, gloves, and surgical or athletic bandages, the ventilating features being sufficient to avoid soreness or foulness. Heretofore, however, it has always been unsanitary and sometimes impossible to wear articles of rubber in the same way; rubber boots are generally lined with cloth which soon becomes foul, disgusting, and unsanitary; rubber cannot be used for gloves or bandages for extended wear; while artificial leather and leather substitutes have hitherto failed of adoption for the same reasons.

The object of our invention is to avoid these drawbacks and permit articles of these materials to be worn next the body with the same impunity as leather articles; other objects are the provision of a new and improved lining or surfacing for such articles; the provision of a lining for articles of body wear of such a nature, such a thickness from point to point, and such a mode of application that cracking or deterioration of both the lining and the article itself shall be avoided; and the provision of certain new and improved articles of body wear.

The essence of our invention consists in this, that a lining consisting of thin, flexible, unbroken, sheets of pure cork is attached by cementing, vulcanizing, or the like to the inner surface of the article, the inner surface of the cork being left naked and un-

covered so as to preserve its porous and absorbent qualities.

In the drawings accompanying and forming a part of this application, wherein are illustrated a few typical embodiments of our invention; Figure 1 is a sectional view of a rubber or artificial leather boot provided with our improvements; Fig. 2 is a view showing the elements of said boot in separated relation and illustrating one mode of making the same; Fig. 3 is a view of a piece of material made in accordance with our improvements and illustrating another mode of fashioning articles of body wear; Fig. 4 illustrates a piece of lining material; Fig. 5 illustrates a glove, Fig. 6 a bandage and Fig. 7 a shoe embodying our invention. These drawings are illustrative only and do not limit us to the articles shown or to the mode of forming the same.

The lining material which we employ is cork, preferably pure, which is cut or shaved into very thin sheets, preferably from 1/128th inch to 3/32nds inch in thickness and of as large size as convenient or possible, the superficial measurements being great as compared with the thickness. Thus we prefer that these sheets shall measure several inches in each direction as the difficulty of fitting together is diminished, though smaller fragments can be used so long as the surface is great relative to the thickness; the desideratum being that the material be not pulverized.

One of these sheets is shown in Fig. 4 and has a soft and cloth like texture, possesses a surprisingly large amount of toughness and elasticity, and can be rolled, rubbed, and kneaded to a remarkable extent. It is preferably made from virgin cork although a usable quality can be cut from blocks of cork dust or granules which have been compacted together under heat and great pressure.

These sheets are secured by flexible cement to the inner surface of the article and this may be done at any stage of the manufacture thereof. Thus the cork sheets may be affixed to the rubber or other material before cutting or forming the same in any degree; or it may be affixed after partial cutting or forming and before assembling; or it may be affixed after partial or complete assembling has taken place. In the case of many arti-

cles a combination of these alternatives are best employed.

Consider, for example, the manufacture of the boot shown in Figs. 1 and 2, which we will assume to be of rubber material. The sole 1, foot 2, and leg 3 are generally formed separately and later joined together. The sole is pressed and partly cured between dies; the foot portion is built on a mandrel and partly cured; the leg is made by rolling up a flat sheet and uniting the edges along a vertical seam at the rear; the parts are then assembled together, a suitable rubber composition applied to the seams, and the curing completed which finishes the heat treatment of the parts themselves and also joins them together. In performing our invention we cut a cork sheet of the proper size to the shape of the sole as shown at 4 and attach it by a raw rubber cement; we cut other cork sheets to suitable patterns as shown at 5 and affix them to the interior of the foot portion by a similar cement after that portion has been formed and prior to attaching the sole thereto; and we similarly cement other sheets 6 to the leg portion prior to rolling the same and even before cutting the same to shape. The various lined portions being then assembled together and subjected to the final curing process the linings are vulcanized to the rubber.

Vulcanization of the lining is not essential and is not ordinarily employed in case the article itself be of a substance other than rubber, as, for example, a cellulose compound or so called "artificial leather". It is important, however, that the attaching medium be of a pliable nature and that the cork sheets be of such a thinness as not to offer undue resistance to the folding or ordinary creasing of the article. For this reason we preferably make the portion 5 of less thickness than the portions 4 or 6, thus avoiding cracking of the foot of the boot in use; we prefer a thickness of the cork of about 1/128th inch at this point, but do not limit ourselves thereto as it may be considerably thicker or somewhat thinner. The portion 4 is comparatively thick since the sole is not seriously flexed while in use, and the softness of the cork, its absorptive power, its ventilating power, and its heat-insulating qualities are peculiarly important at this point; we prefer a thickness of about 1/32 inch at this point, but do not limit ourselves thereto. The portion 6 is also, preferably of comparatively great thickness since the leg is not subject to serious flexing and the heat-insulating qualities of the cork are peculiarly desirable at this point to ward off rheumatic affections from the lower leg which is especially susceptible.

The fact that the sheets are of large area compared with their thickness enables them to be held firmly in place and inhibits their

becoming ruffed up and ground off by the friction of the foot, as would be the case with granular material, and also reduces the shielding action of the cement which would tend to submerge and smother a pulverulent material. The cork lining can also be washed and disinfected easily which is not the case with cloth; cloth also lacks the heat-insulating and ventilating qualities of our material.

In Fig. 3 we have shown a sheet 10 of rubber, cellulose composition, or "artificial leather," coated with cork sheets as previously described, and marked with the patterns of glove-blanks 11, shoe-sole 12, athletic bandage 13, and shoe tops 14, 14, which are subsequently to be cut therefrom and joined together in the suitable or any well-known manner. In Figs. 5, 6, and 7, we have shown the glove, the bandage and the shoe made therefrom.

The invention is also applicable to a partial covering of the body-wear article, as in the case of a rubber boot which is lined only as to the sole, or foot portion; or to an article of body wear of which only a part is made of impervious material, such as a "tennis" shoe wherein the rubber or composition sole is covered with our improved lining and the upper, being of porous canvas or duck, is left bare. We esteem it important that the securing of these sheets be effected in such a way that the surface pores of the cork shall not be plugged or obliterated or submerged and their absorptive power impaired. As an example we recommend the employment of a rubber cement applied to the inner surface only which will adhere to the surface portions but without penetrating to any material extent; and without confining ourselves to this one material, we include this mode of attachment under the term "superficial adhesion." We also employ the expression "sheets of integral cork" as denoting sheets which, prior to attachment, have an integral, continuous character. The word "rubber" includes the various compositions and substitutes used in the arts.

It will be understood that other articles can be made and that other methods may be employed within the scope of our invention.

Having thus described our invention what we claim is:—

1. An article of body wear made of flexible material conforming closely to that portion of the body to which it is applied and having its inner surface covered with naked sheets of cork, the thickness of the cork sheets being very small relatively to their superficial area.

2. An article of body wear made of a flexible, non-porous, material whose inner surface is covered with naked sheets of cork, the superficial area of said sheets being

great as compared with their thickness and said sheets being attached to the non-porous material by superficial adhesion.

3. An article of body wear made of a flexible non-porous, material to whose inner surface is attached by flexible cement a naked lining consisting of thin sheets of integral cork constituting a single layer, said sheets being accurately fitted together at their edges and the individual sheets having a superficial area which is large relatively to their thickness.

4. An article of body wear made of a flexible impervious material whose inner surface is lined with naked sheets of integral cork attached thereto by superficial adhesion, the thickness of the cork being such

that the stiffness of the impervious material will not be increased materially and the separate sheets being of large superficial measurement compared with their thickness.

5. A rubber boot lined with sheets of naked cork secured in place by superficial adhesion.

6. A rubber boot lined with sheets of naked cork secured in place by superficial adhesion, the thickness of the cork sheets being less in the foot portion than in the sole or leg portions and being in all cases small in comparison with the superficial area of those sheets.
